DESIGN FOR A CALENDAR-STAND.

SPECIFICATION forming part of Design No. 20,442, dated January 6, 1891.

Application filed November 21, 1890. Serial No. 372,256. Term of patent 3½ years.

To all whom it may concern:

Be it known that I, GILBERT L. CROWELL, Jr., a citizen of the United States, residing in Arlington, county of Hudson, and State of New Jersey, have invented and produced a new and original Design for Calendar-Stands; and I do hereby declare the following specification, taken in connection with the accompanying drawings, and forming part of the same, to be a description thereof.

Figure 1 is a front view of a calendar-stand, showing my design. Fig. 2 is a view in elevation of one of the sides thereof, showing my design.

15 The leading feature of my design consists in a representation in relief composed of irregularly-placed scrolls and interspersed within the central scrolls corollas or flowers with open petals.

20 The top of the face or front of the stand has a triangular surface with a representation in relief composed of irregularly-placed scrolls a, extending upward from the sides of the calendar-stand to a tapering point, and interspersed within the central scrolls a corollas or flowers with open petals b. The bottom of the face or front of the stand has a square surface with a representation in relief composed of irregularly-placed scrolls a, extending from side to side of the stand, and interspersed among the scrolls a corollas or flowers with open petals b.

Each side of the calendar-stand exhibits irregularly-placed scrolls a, tapering from top to bottom of the sides and increasing in size, and interspersed between the scrolls a corollas or flowers with open petals b and escalated shell-like leaves c.

I claim—

The design for a calendar-stand, as herein shown and described.

In testimony whereof I affix my signature in presence of two witnesses.
